UNITED STATES PATENT OFFICE.

OTTO KAUFMAN, OF YOUNGSTOWN, OHIO.

MANTLE-CUTTING MACHINE.

1,086,671.

Specification of Letters Patent. Patented Feb. 10, 1914.

Application filed April 12, 1912. Serial No. 690,395.

To all whom it may concern:

Be it known that I, OTTO KAUFMAN, a citizen of the United States, residing at the city of Youngstown, county of Mahoning, State of Ohio, and whose post-office address is care of the Block Light Co., in said city, have made a new and useful Improvement in Mantle-Cutting Machines, of which the following is a specification.

10 My invention relates to a machine for severing mantle blanks from a continuous web or stocking so that each blank will be of the desired length. As many blanks may be simultaneously severed as there are webs 15 and one or more webs may be run through the machine at one time, it being understood, however, that in the embodiment of my machine hereinafter set forth, the severed portions will be of the same length. The action 20 of the machine is entirely automatic throughout and requires no attention, save the general supervision more or less necessary for all automatic machines.

For a further description of my invention, 25 reference is to be had to the accompanying drawings, forming a part hereof, in which—

Figure 1 is a side elevation of a machine embodying my invention. Fig. 2 is a top plan view of the same. Fig. 3 is a rear elevation of the machine. Fig. 4 is a front elevation of the same. Fig. 5 is a sectional view taken on line 5—5 of Fig. 2, looking in the direction of the arrows. Fig. 6 is a sectional view of the machine taken on line 35 6—6 of Fig. 2, looking in the direction of the arrows. Fig. 7 is a sectional view showing the cutter and a part of its driving mechanism. Fig. 8 is a sectional view taken on the line 8—8 of Fig. 7, looking in the direction of the arrows. Figs. 9—12 inclusive 40 show a cam for elevating or depressing the cutter and the roller coöperating therewith, Figs. 9 and 10 showing the cam in the position where it elevates the roller and Figs. 11 45 and 12 show the roller in its lowest position. Figs. 13 to 16 inclusive show the gearing for driving the feed rolls.

Throughout the various views of the drawings, similar reference characters designate 50 similar parts.

My improved machine 1 is provided with suitable legs 2 which carry a table 3 on which the mechanism of the machine is mounted. A pair of standards 4 and 5 are 55 provided with vertical slots near their upper ends, so as to carry rods 6 and 7 on which

the spools or bobbins 8 are mounted that carry suitable mantle webs 9. Two of these spools are shown, and it is obvious that more may be used by simply increasing the number of standards or, if desired, only one web need be used, according to the desires of the operator. The webs 9 pass under a suitable and horizontally disposed bar 10 which forms a guide transversely of the direction 60 of the movement of the web 9 when being fed into the machine. This bar 10 is carried by suitable standards 11, one near each end, which rise from the plate 12 that is carried by suitable sides 13 from the table 3. The web 9 then passes between suitable vertical guides 14, each of which is provided with a rod 15 that runs into a standard 16, where it may be clamped by means of a suitable set screw 17 in any desired position within its range of adjustment. The object of the vertical guides 14 is to cause the webs 9 to be properly placed between the feed rollers 18 and 19, which will be described below. The plate 12 is suitably slotted, so as to permit 70 the lower roller 19 to pass through this plate in such a manner that its highest line will be a little above the level of the plate 12. This plate is also slotted at 20, so as to permit a cutter 21 to pass through the same at 75 the desired interval.

The feed rollers.—The feed rollers 18 and 19 are mounted so as to be driven together as will appear below. These rollers have their journals running through suitable 80 bearings 22, which are so arranged and designed that these rollers are normally kept in contact by the tension of springs 23 placed under suitable caps 24, one spring and cap for each bearing 22 and the tension 85 is adjusted by means of screws 25 applied to these caps and uniting them with the bearings. This tension enables the rolls 18 and 19 to firmly grip the web 9, which is fed therethrough and feed the same whenever 90 these rollers are rotated. The rollers have to move in unison, because they are of the same diameter and they are geared together by identical pinions 26 and 27, the pinion 26 being connected to the roller 18 and the 95 pinion 27 to the roller 19. The roller 19 is also connected, at the other end, to another pinion 28, which is fixed to the journal shaft of this roller and outside the bearing 22 and this pinion 28 meshes with an idle gear 29, 100 mounted on a stud shaft 30 in a bracket 31, one end of which is mounted on a stud shaft

32 fixed in the frame of the machine and on which a gear 33 is mounted, so as to mesh with the gear 29. The gear 33 is fixed to an interrupted gear 34, which is also mounted 5 on the stud shaft 32, so that the gears 34 and 33 have the same angular movement. The gear 34 meshes with a corresponding gear 35 fixed to a suitable shaft 36, which is mounted in the supports 13 in any suitable 10 bearings and this shaft 36 may be considered the main shaft of the machine. It is driven by a suitable sprocket wheel 37, which is fixed to this shaft 36 in any suitable manner and this sprocket wheel is 15 driven by any suitable sprocket chain, not shown. The bracket 31 is provided with a suitable arm 38 that projects downwardly and in such a manner that its central slot is concentric with the axis of the shaft 32. 20 A suitable bolt 39 mounted on the frame of the machine passes through the slot in the projection 38 and enables the operator to adjust the bracket 31 in any desired position. This position will vary with the length of 25 the mantle to be severed, because the gears as shown can operate for only one length of mantle and when a mantle of a different length is to be severed, the gears may be correspondingly changed, so as to give the 30 rollers 18 and 19 a greater or less angular movement for each shifting of the cutter 21, as is obvious.

The clamp.—By referring to Fig. 5, it will be seen that the main shaft 36 carries 35 a suitable cam 41, which runs against and controls a roller 42, mounted on a suitable spindle 43, fixed to a shaft 44 running at right angles thereto and journaled in one of the supports 13. This shaft 44 (see Fig. 40 6) carries a suitable segmental gear 45, which meshes with a corresponding gear 46, mounted loosely on a suitable shaft 47, which will be described below. The gears 45 and 46 are identical and each has teeth 45 meshing with racks 48 and 49, respectively, on suitable standards 50 and 51 that pass through ears or guides 52 secured to the standards 13. These standards 50 and 51 are each provided with suitable coiled 50 springs 53, which are depressed when these rods are lowered, and at their tops, these posts are united by suitable angle bars 54 and 55 connected by a crossing 56. The free ends of these bars 54 and 55, respectively, are 55 provided with downwardly extending rods 57 and 58, which have suitable nuts 59 and each runs from a suitable sleeve 60 just below the nut 59 and below the angle bars 54 and 55 are suitable coiled springs 61, which 60 press against suitable nuts 62. Below the nuts and within them the rods 57 and 58 are screw threaded and secured to a suitable presser foot or stripper 63, which is slotted at 64, so as to permit the cutter 21 to extend 65 through the slot 20 and into a slot 64, so

that the fabric of the webs 9 will be severed with a shearing action and without loose threads. From the foregoing, it is obvious that once every revolution of the shaft 36, the cam 41 causes the roller 42 to be elevated and this elevation of the roller 42 depresses the presser foot 44 so that it clamps the fabric in place over the cutter 21 and this cam 41 is so shaped that the presser foot clamps the fabric all the time the cutter 21 is in operation and nearly all the time that the rollers 18 and 19 are idle. 70

The cutter.—By turning to Figs. 7 to 12 inclusive, it is easy to understand the action of the cutter 21. This cutter 21 is elevated and depressed by mechanism driven from the shaft 36, which is provided with a suitable cam 65 for this purpose. This cam 65 is arranged to raise and lower a corresponding roller 66, mounted on a suitable stud shaft 67 fixed to a shaft 47 above described, which is journaled in a suitable bearing 68 that runs from a side 13. The shaft 47 is also fixed, to an arm 69, the outer end of which is slotted to engage a pin 70 on a suitable support 71, which runs to a shaft 72, on which it is loosely mounted, so that the shaft 72 can rotate therein. This shaft 72 is mounted in a side 13 and is driven at a high speed by a suitable pulley 73, which is fixed to this shaft and receives a belt from any suitable source, not shown. The cutter 21 is mounted on a suitable mandrel 74 in the conventional manner and this mandrel 74 is provided with a suitable groove 75 to receive a belt or cord 76, that runs to a pulley 77 fixed on the shaft 72, so that the cutter 21 is rotated at a high velocity and driven from the shaft 72. It will be noted that the cam 65 is made, so as to elevate the roller 66 for a shorter time than the cam 41 elevates the roller 42, so that the elevation of the cutter 21, above described, is for a shorter period than the depression of the presser foot or stripper 63. 90

Operation.—In view of the foregoing, the operation of my improved mantle cutting machine will be readily understood. Assuming the parts to be as shown in Fig. 1, (except some parts are omitted, as is obvious, to more clearly reveal the structure) and power is applied to the sprocket wheel 37 and the pulley 73, the mantle web or webs 9 are then passed under the guide 10 and between the guides 14 to the rollers 18 and 19, which intermittently move the web under the clamp 64, where it is clamped and while so clamped, the cutter 21 rises and severs the fabrics and immediately retires. The clamp is then removed, the feed rollers 18 and 19 again have an angular movement for a predetermined distance, feeding a predetermined length of fabric under the clamp 64 and when this movement ceases, the clamp is depressed, the cutter 21 rises and 100

110

115

120

130

this operation is repeated indefinitely, until the webbing is exhausted and more is inserted and severed in the same manner. All the operator has to do is to supply the raw material, remove the finished product and keep the machine properly oiled and in proper condition and from time to time make suitable adjustments either for wear or for the various length of mantles, which 10 may be desired.

While I have shown and described one embodiment of my invention, it is obvious that it is not restricted thereto, but that it is broad enough to cover all structures that 15 come within the scope of the annexed claims.

What I claim is:—

1. In a machine of the class described, a cutter, means for rotating the same at a high 20 velocity, a presser foot movable vertically, and means for moving the cutter vertically and holding it elevated for a shorter period than that of the depression of the presser foot.
2. In a machine of the class described, a revolute cutter, means for rotating the same and angularly disposed rollers for intermittently moving a web, and a vertically movable clamp for clamping said web, and 30 means for moving the cutter vertically and holding it elevated for a shorter period than that of the depression of the clamp.
3. In a machine of the class described, a revolute cutter, means for rotating the same and angularly disposed rollers for intermittently moving a web, a vertically movable clamp for clamping said web and means for moving the cutter vertically to sever the web during its period of rest and means for 40 shifting the cutter while the fabric and web are held.
4. In a machine of the class described, a main shaft carrying a plurality of cams, and

an interrupted gear, feed rollers and means for operating the same from said interrupted gear, a vertically movable clamp and means for operating the same from one of said cams, a vertically movable rotary cutting mechanism and means for driving the same, and means for shifting the same while 50 said shaft holds the fabric and the web.

5. In a machine of the class described, means for supporting a plurality of spools containing webbing, a feeding device, means for driving a plurality of webbings through 55 said feeding device and means for operating the same intermittently, a clamping device, means for clamping the webbings while said feeding device is in operation, and rotary means for severing the webbing while held 60 by said clamping device.

6. In a machine of the class described, means for supporting a plurality of spools containing webbing, means for feeding a plurality of webbings and a clamp for securing said webbings while being cut, and rotary means for severing said webbing, 65 said rotary means being shiftable while the fabric and web are being held.

7. In a machine of the class described, 70 means for supporting a webbing, means for guiding the webbing, means for intermittently feeding webbing, means for clamping said webbing while not being fed, and a rotary means for severing the webbing while 75 being clamped, said rotary means being shiftable while the fabric and web are being held.

Signed at the city of Youngstown, in the county of Mahoning, and State of Ohio, this 80 10th day of April, 1912.

OTTO KAUFMAN.
